CLAIM

I claim the ornamental design for a mouse pad bottom, as shown and described.

DESCRIPTION

FIG. 1 is a first embodiment of the mouse pad bottom showing my new design;

FIG. 2 is a second embodiment of the mouse pad bottom; FIG. 3 is a third embodiment of the mouse pad bottom; and, FIG. 4 is a top perspective view of the mouse pad for which the bottom views are shown in FIGS. 1, 2, and 3.

The broken line illustration in FIG. 4 indicates environmental structure of the mouse pad and is not considered part of the claimed design.

In particular respective species of the embodiments of the design shown in each FIGS. 1-3, the front and rear end portions represent fabric covering portions, and the intermediate portion between the front and rear end portions represent a surface of compressible foam.
